UNITED STATES PATENT OFFICE.

CARL PEDERSEN, OF FORT WAYNE, INDIANA.

WRENCH.

1,154,544.

Specification of Letters Patent. Patented Sept. 21, 1915.

Application filed April 9, 1915. Serial No. 20,258.

To all whom it may concern:

Be it known that I, CARL PEDERSEN, a citizen of the United States, residing at Fort Wayne, in the county of Allen and State of Indiana, have invented new and useful Improvements in Wrenches, of which the following is a specification.

This invention relates to improvements in combined wrench and clamp.

One of the objects of the invention is to provide a device of this character which shall include a stationary jaw having a toothed shank, a movable jaw upon the shank, two pawls arranged within the movable jaw and eccentrically mounted upon a suitable shaft or bearing, the said shaft or bearing being provided with an operating lever which is oscillated to cause the dogs to each successively engage with the teeth of the shank to move the movable jaw toward the stationary jaw or to lock both of the dogs in engagement with two of the teeth of the shank, when the jaws are to be employed as a clamp, a single piece being arranged upon one of the said dogs whereby the same may be actuated to swing the said dog to cause the same to contact with the second dog and to bring both of the dogs out of engagement with the teeth, thus providing for the ready adjustment of the movable jaw in either of its directions of travel.

A further object of the invention is to provide a device of this character which shall embody the desirable features of simplicity in construction, cheapness, accuracy and thorough effectiveness in operation.

In the drawings: Figure 1 is a side elevation of a wrench or clamp constructed in accordance with the present invention, Fig. 2 is a transverse sectional view approximately on the line 2—2 of Fig. 1. Fig. 3 is a longitudinal sectional view approximately on the line 3—3 of Fig. 2, Fig. 4 is a similar sectional view approximately on the line 4—4 of Fig. 2, Fig. 5 is an edge view of the wrench, Fig. 6 is a sectional view on the line 6—6 of Fig. 1, Fig. 7 is a sectional view on the line 7—7 of Fig. 1, Fig. 8 is a perspective view of the shaft for the dogs, Fig. 9 is a similar view of one of the dogs, and Fig. 10 is a similar view of the second dog.

Referring now to the drawings in detail, the numeral 1 designates the head or jaw of the stationary member of the device, and 2 the angular shank therefor. This shank is preferably rectangular in cross section and

has one of its edges provided with transverse teeth 3. The teeth include substantially straight shoulders and transverse walls connecting the shoulders.

The numeral 4 designates the carriage of the movable jaw, the jaw proper comprising a plate 5 arranged adjacent the bore of the carriage 4 and having its engaging face serrated, as indicated by the numeral 6, and likewise the engaging face of the jaw 1 may be similarly serrated as indicated by the numeral 7. The rear face of the carriage is provided with a substantially right angular depression, forming a pocket 8. Side plates 9 are secured to the opposite faces of the sides of said carriage and provide side members or walls for the pocket 8. These side plates 9 are provided with alining circular openings 10, the said openings receiving the opposite ends of the shaft 11. The openings 10 are of a greater diameter than is the cross sectional diameter of the shaft 11, and the peripheral walls of the said openings 10 are threaded to receive peripheral threads 80 provided upon bushing or bearing members 12—12, the said members 12 being formed with suitable openings within which the ends of the shaft 11 are journaled. The shaft 11 is provided with a pair of eccentrically arranged cam wheels 13 and 14 respectively which are disposed within the pocket 8, and the said cam wheels are preferably of a less cross sectional diameter than the area of the openings 10 so that the shaft may be 90 inserted laterally through the said openings 10. It will be noted that the eccentric or cam surfaces 13 and 14 are disposed in opposite directions upon the shaft 11, and one of the ends of the shaft 11 projects a suitable distance beyond its bearing 12, the said end being formed upon one of its sides with a longitudinally extending depression 15, said end is adapted to enter an opening 16 provided in the head portion 17 of an operating handle 18.

The numeral 19 designates the transverse depression or slot formed in the head 17 and which communicates with the bore 16 thereof, and this slot 19 is adapted to register 105 with the depression 15 so that a locking key 20 may be inserted within the said alining depressions to lock the handle upon the shaft 11.

Arranged within the pocket 8 and mounted upon the respective cam or eccentric members 13 and 14 are the body members 21

and 22 of a pair of dogs indicated by the numerals 23 and 24 respectively. The adjacent or meeting faces of the bodies are reduced, equaling the thickness approximately one-half of the cross sectional diameter of the dogs proper, so that the dog 23 underlies the arcuate inner edge of the dog 24, the said dogs extending through the pocket 8 and engaging with the teeth 3 of the shank 2. The bodies of each of the dogs 23 and 24, at its corner diametrically opposite that formed with the dog proper, is provided with lugs 25 and 26 respectively, each of said lugs being engaged by one of the ends of two arm springs 27 and 28 respectively, and these springs have their second arms received within recesses or depressions provided in the rear wall of the pocket 8, while still again, the transverse bolt or pin member 29 is engaged with the said springs 27 and 28 to retain the same in the pocket 8. Extending outwardly from the shoulder 25 is a finger 30, the said finger being projected through the pocket 8, and it will be noted that by actuating this finger to swing the body 21 of the dog 23, the said dog 23 which, as previously stated, underlies the dog 24, and will automatically swing the said dog and of course swing the dog 23 out of engagement with the teeth 3 of the shaft 2.

The operation of the device may be briefly described as follows: By swinging the handle 18 from the position shown in the full lines in Fig. 1 of the drawings to the position indicated by the dotted lines in the said Fig. 1, and by oscillating the said handle to bring the same successively in such positions, it will be noted that the cam portions 13 and 14 will successively force each of the dogs 23 and 24 respectively alternately into and out of engagement with the teeth 3, thus causing the jaw of the carriage 4 to travel in the direction of the head or jaw 1, and further that when the handle is arranged at an approximate right angle to the wrench or in the position illustrated by the full lines in the said Fig. 1, both of the dogs 23 and 24 are in engagement with two of the

teeth 3, thus providing a clamp between the 50 same. As previously stated, by operating the finger 30, the jaws will be brought out of engagement with the teeth so that the carriage 4 may be moved longitudinally 55 upon the shank 2 to bring its head either toward or away from the body of the stationary jaw.

From the above description, taken in connection with the accompanying drawings, the simplicity of the device, as well as the 60 advantages thereof will, it is thought, be perfectly apparent to those skilled in the art to which such invention appertains without further detailed description.

Having thus described the invention, what 65 I claim is:

In a wrench, a stationary jaw having a toothed shank, a movable jaw including a carriage mounted upon the shank, said carriage including a pocket, a shaft journaled 70 in the side walls of the pocket, the portion of the shaft in the pocket having reversely arranged cam members, two dogs, each of said dogs having its body portion reduced to provide contacting faces to permit the 75 engaging end of one of the dogs being disposed forward and in a line with the active end of the other dog, each of said dogs having their bodies provided with openings equaling the respective cam members upon 80 the shaft and receiving the said cam members, springs co-acting with the dogs for forcing their engaging ends into contact with the teeth of the shank, and one of the dogs having an angular finger-piece extending through the pocket in the carriage to permit of the swinging of said dog to bring the same into contact with the other dog to raise both of the dogs out of engagement 85 with the teeth of the shank, and a handle 90 for the shaft.

In testimony whereof I affix my signature in presence of two witnesses.

CARI PEDERSEN.

Witnesses:

CARL PASSE,
HENRY LAGEMANN.
